UNITED STATES PATENT OFFICE.

EDWARD F. HEDDERICH, OF FLORA, INDIANA, ASSIGNOR TO THE DAIRY CREAM SEPARATOR CO., OF LEBANON, INDIANA, A CORPORATION.

MACHINE-FRAME.

No. 889,683.

Specification of Letters Patent.

Patented June 2, 1908.

Application filed April 20, 1907. Serial No. 369,228.

To all whom it may concern:

Be it known that I, EDWARD F. HEDDERICH, a citizen of the United States, and a resident of Flora, in the county of Carroll and State of Indiana, have invented a new and Improved Machine-Frame, of which the following is a full, clear, and exact description.

The purpose of this invention is to provide a machine frame of novel construction, which is especially well adapted for the reception and support of operative mechanism employed for rotating the holder of a hand cream separator device.

The invention consists in the novel construction of parts and their combination in a machine frame, as is hereinafter described and defined in the appended claims.

Reference is to be had to the accompanying drawings forming a part of this specification, in which similar characters of reference indicate corresponding parts in all the figures.

Figure 1 is a rear elevation of the improved machine frame; Fig. 2 is a sectional side view of the improved frame and of machine elements within it, shown for illustrating the advantages afforded by the special construction of the frame, the section being substantially on the line 2—2 in Fig. 1; Fig. 3 is an enlarged sectional side view of portions of the frame and of machine elements mounted therein, the line of section being indicated at 3—3 in Fig. 4; Fig. 4 is a sectional plan view of details of the frame, substantially on the line 4—4 in Fig. 3. Fig. 5 is a detached plan view of an attachable bracket frame, that is a detail of the invention, and Fig. 6 is an enlarged vertical transverse sectional view of details, substantially on the line 6—6 in Fig. 4.

It may here be explained that the improved machine frame is particularly designed for the support in operative positions of an association of machine elements, employed for the rotation of a vessel containing milk and cream, for the speedy separation of the cream by centrifugal action. And to render clear the special advantages of the present improvements, the mechanism normally held in and on the frame is illustrated, and will be briefly described but not claimed in this case, as the right is reserved for protecting said mechanism by a separate patent.

As represented in the drawings, the improved machine frame comprises a preferably circular base portion 10, that is recessed

to form a receptacle or chamber 10^a having a bottom wall 10^b, said base portion being supported upon legs 10^c. A cylindrical hollow column 11 forms the body of the machine frame, and as shown the lower portion of said column is flared or given bell-shape, the lower edge of this flared wall 11^a having a diameter substantially equal with that of the base portion 10, whereon it is seated and preferably attached by a hinge joint *a*, this connection permitting the hollow body 11 to be rocked on the recessed base 10, so as to remove it laterally from over the latter and freely expose and give access to said base.

Upon the bell-shaped formation 11^a, at the side of the hollow body portion 11 of the frame, a cylindrical wall 12 is formed that is vertical, this wall constituting the lower portion of a diametrically enlarged chamber 13, which is designed to receive and support for free rotation a suitable milk and cream holding vessel, not shown. The flared portion 11^a of the hollow body 11 of the frame may be reinforced interiorly by a centrally perforated diaphragm wall 11^b.

The bottom wall of the vertical cylindrical shell 12 is centrally perforated and threaded in said perforation to receive a centrally perforated box 12^a, and below said box an integral boss 12^b is formed on the bottom of the frame body 11, and is spaced from the box 12^a. In the boss 12^b a vertical threaded perforation is formed that receives a step block 12^c, the latter having an axial socket formed from its upper side, of a suitable depth, the use of which will be hereinafter explained.

The upper end of the column 11 is partially closed by a box formation 11^c, that is integral therewith and overhangs this end as appears in Fig. 2. In the box formation 11^c, a bore *b* is formed that is at right angles with the axis of the column 11, and consequently is horizontal when the body of the frame and its base 10 are supported on a level floor or other equivalent support.

As is shown in Figs. 2, 3 4 and 6 a cross bar 10^d is adjustably secured by its ends at opposite points on the side wall of the column 11, said ends of the cross bar being seated upon lugs *c*, *c'* which project inwardly from said side-wall of the column. In the lug *c*, two spaced and slightly elongated perforations *d* are formed, and in the end of the

cross-bar 10^d that seats thereon, two perforations are formed opposite the perforations *d*, said registered perforations receiving clamping bolts *d*¹. Upon the opposite lug *c*¹ 5 two spaced depending ears are formed that are oppositely perforated, these perforations being threaded for reception of set-screws *d*². A depending abutment lug *d*³, shown by dotted lines in Fig. 4, is positioned between the 10 inner ends of the set-screws *d*². In the lug *c*¹, behind the set-screws *d*², laterally elongated and spaced perforations are formed, that register with perforations in the end portion of the cross bar 10^d, these opposed 15 perforations in the cross bar and lug *c*¹ receiving two securing bolts *c*². It will be seen, that at the special construction of the cross bar 10^d, and details connected therewith which have been described, adapt the 20 cross bar to receive a limited lateral adjustment toward or from the boss 12^b, the advantage of which will be hereinafter explained.

In the hollow body 11 of the machine frame, a shaft A is centrally positioned and adapted for rotation, by means which will now be described. Centrally in the cross bar 10^d, an opening is formed as shown at *g* 25 in Fig. 4, and through the diaphragm wall 11^b and said perforation in the cross bar, the shaft A is loosely passed. Upon the lower side of the cross bar 10^d a depending hub *h* is formed, having an axial threaded perforation, wherein is screwed a step block *h*¹ that 30 receives the lower end of the shaft A and supports the same.

In the lower side of the box formation 11^c 35 is a vertical perforation, that is at the axial center of the column 11^c; and in said perforation a bearing block *b*¹ is secured which is vertically bored, and receives the upper journal end of the shaft A. Upon the upper portion of the shaft A, below and near the journal end thereof, a bevel pinion A' is 40 secured.

In the horizontal bore *b* a short driving shaft B is loosely inserted, having a spur bevel gear B' secured on one projected end thereof, said gear wheel having meshed engagement with the bevel pinion A'. On the 45 opposite projected end of the shaft B, a crank handle B² is mounted and secured, which affords means for the manual rotation of the driving shaft B and upright shaft A through the medium of the gears A', B'. Upon the upright shaft A, between the diaphragm wall 11^b, and the cross bar 10^d, a worm gear wheel C of considerable diameter 50 is mounted, and secured. A spiral toothed pinion or small worm gear C' is formed or secured on a short spindle C² which meshes with the worm gear wheel C, said spindle at 55 its ends respectively having running engagement with the bearing box 12^a and step block 12^c. It will be seen that the lateral

adjustment of the cross bar 10^d by means hereinbefore described, enables the exact meshed engagement of the worm gears C and C', and permits wear of said parts to be taken up.

The spindle C² may have any desired length, and be coupled by any preferred means with a vessel held rotatably in the chamber 13, for rotation of said vessel and its contents, this being effected by the mechanism described, that is specially well adapted for operating a hand cream separator.

The provision of a hinged base portion for the machine frame is of great advantage, as all drippings of grease from the working mechanism in the hollow frame are caught in the base 10, and may be removed at any time by simply rocking the column 11 on the base 10 so as to fully expose the open top of the latter and thus afford free access to the inside of the base for cleansing the same. Coating with the machine frame elements that have been described, is an important adjunct comprising an adjustable bracket 90 having novel form, this being clearly shown in Figs. 1 and 5. The bracket consists of an arm 14 having a circular ring clamp at one end thereof, which is formed with a detachable section 14^a hooked at *i* upon one end of a semicircular integral section 14^b of the ring clamp, the opposite end of the detachable section terminating in a flat flange *k*, that is adjustably secured upon the arm 14 by a screw bolt *i*¹ as is clearly shown in Fig. 5. 95 At the opposite extremity of the arm 14, an integral clamping ring 15 is formed, having two radial limbs 15^a formed thereon, and to give resilience to the body of the ring 15, one limb 15^a is longitudinally slotted as shown at *m* in Fig. 5, forming two portions that may be clamped toward each other by the screw *m*¹. The portion of the bracket comprising the ring clamp having the sections 14^a, 14^b 100 is mounted upon the column 11, above a circumferential bead *n*, formed on said column and seats thereon, as shown in Fig. 1, said members 14^a, 14^b being hooked together at *i*, and secured in a clamped condition by the bolt *i*¹.

In the lower edge of the clamping ring 14^a, 14^b an incline *o*, is formed and is in engagement with a pin *o*¹, which projects from the column. It will be seen, that when free to be moved the arm 14, may be swung around on the column into any desired position, its contact with the pin that raises the lower edge of the clamping ring 14^a, 14^b, by its sliding engagement with the incline *o*, reducing friction, so that the arm may be moved with but slight manual force. The arm 14 is held in any desired position, by a clamping adjustment of the screw *i*¹. The other clamping ring is designed for holding in position a milk holding vessel, not shown.

Having described my invention, I claim as new, and desire to secure by Letters Patent:

1. In a machine frame of the character described, the combination with a hollow body portion, of an adjustable cross bar on the lower part of said hollow body portion, and a base hinged upon the body portion below said cross bar.
- 10 2. In a machine frame of the character described, the combination with a cylindrical hollow body portion having a flared lower end, and a recessed base portion hinged on

said flared end of the body portion; of a cross bar, said flared end of the body portion having lugs thereon on which the cross bar is seated, and means for adjustably securing the cross bar on said lugs.

In testimony whereof I have signed my name to this specification in the presence of two subscribing witnesses.

EDWARD F. HEDDERICH.
